US0D1018011S

(12) **United States Design Patent** (10) **Patent No.:** **US D1,018,011 S**
(45) **Date of Patent:** **** Mar. 19, 2024**

(54) **REMOTE CONTROL**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/835,283**

(22) Filed: **Apr. 18, 2022**

Related U.S. Application Data

(60) Continuation of application No. 29/674,636, filed on Dec. 21, 2018, now Pat. No. Des. 967,800, which is a continuation of application No. 29/485,556, filed on Mar. 20, 2014, now Pat. No. Des. 836,612, which is a continuation of application No. 29/432,443, filed on Oct. 15, 2012, now Pat. No. Des. 704,167, which is a continuation of application No. 29/404,056, filed on Oct. 14, 2011, now Pat. No. Des. 669,452, which is a continuation of application No. 29/391,544, filed on May 10, 2011, now Pat. No. Des. 649,138, which is a continuation of application No. 29/366,344, filed on

Jul. 23, 2010, now Pat. No. Des. 642,161, which is a division of application No. 29/345,286, filed on Oct. 13, 2009, now Pat. No. Des. 620,456.

CLAIM

The ornamental design for a remote control, as shown and described.

DESCRIPTION

FIG. 1 is a bottom front perspective view of a remote control showing the claimed design;

FIG. 2 is a bottom rear perspective view thereof;

FIG. 3 is a top front perspective view thereof;

FIG. 4 is a top rear perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The shade lines in the figures show contour and not surface ornamentation.

The broken lines in the figures show portions of the remote control that form no part of the claimed design.

1 Claim, 4 Drawing Sheets

FIG. 1**FIG. 2**

FIG. 5

FIG. 6

FIG. 7

FIG. 8

FIG. 9

FIG. 10
